UNITED STATES PATENT OFFICE.

WILLIS E. LAMB, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE TRUNKING SYSTEM.

1,193,160.

Specification of Letters Patent.

Patented Aug. 1, 1916.

Application filed September 1, 1911. Serial No. 647,146.

To all whom it may concern:

Be it known that I, WILLIS E. LAMB, a citizen of the United States of America, and resident of Chicago, Cook county, Illinois, have invented certain new and useful Improvements in Automatic Telephone Trunking Systems, of which the following is a specification.

My invention relates to automatic or semi-automatic telephone systems, and more particularly to an improved construction in a non-numerical trunking switch for use in such a system.

My invention is in the nature of an improvement upon the non-numerical trunking switch described in the application of F. J. Truby for improvement in automatic trunking systems, Serial No. 603,303, filed January 18, 1911, in that it relates to a rotary 20 non-numerical switch the wipers of which rotate in but one direction and do not return to normal position. When a connection involving the line switch is released, the wipers remain resting upon the contacts of the 25 trunk over which the connection was established, but the line is disconnected from the wipers. If this trunk line is idle when the next call is made through this switch, the line simply becomes connected with the wipers, the 30 wipers themselves remaining stationary. If the trunk upon which the wipers are resting is busy when a call is made, the switch automatically rotates to an idle trunk before the line is cut through to the wipers. My line 35 switch is an improvement over the line switch of Truby, referred to above, in that it is simpler and requires fewer relays. This simplification is obtained by arranging a single relay so that it may perform both the 40 duties of a cut-off relay to cut off the line relay, and a line-switching relay to connect the line with the wipers. This cut-off relay is so arranged that it is capable of cutting off the line relay when the line to which the 45 switch belongs is either calling or is called, while it operates as a line-switching relay to cut the line through to the wipers only when the line is calling.

These and other objects of my invention 50 will be more clearly understood by reference to the accompanying drawings, in which I

have illustrated my improved non-numerical trunking switch in connection with a full automatic two-wire system—that is, a system in which the switches are controlled 55 over a metallic circuit.

In the accompanying drawings Figures 1 and 2 show a complete connection between a calling substation A and a called substation A' in a system embodying the principles of 60 my invention. Fig. 3 is a diagrammatic representation of the essential parts of the subscriber's individual switch C (Fig. 1).

The connection represented in Figs. 1 and 2 is established through the medium of a 65 subscriber's individual or line switch C, first selector D, second selector E and connector F. The general character of automatic exchanges employing line switches, selectors and connectors are well known in the 70 art and will not be explained in detail herein.

The subscribers' substations A and A' may be of any suitable character. As herein shown, the substation A comprises the usual 75 receiver 2, transmitter 3, switch hook 4, ringer 5 and condenser 6. Being an automatic substation, it is also provided with an automatic calling device comprising a pair of interrupter springs 7 and 8 and a toothed 80 impulse wheel 9. The impulse wheel 9 is secured to a shaft 10 to which there is also attached a dial (not shown) provided with finger holes. In order to call any digit, the calling subscriber rotates the dial through 85 the medium of the finger holes and then allows it to return to normal position. During the return motion the impulse wheel 9 separates the springs 7 and 8 a number of times corresponding to the digit called. 90

The subscriber's individual switch C comprises a set of wipers 11, 12 and 13 carried upon a suitable rotary shaft (not shown in Fig. 1) which is controlled by a motor magnet 14. The wipers 11, 12 and 13 are adapted 95 to rotate over and make connection with banks of contacts which form the terminals of trunk lines leading to the selectors D. The line switch C is of the non-releasing type—that is, the wipers never return to 100 normal position, but always rotate in the same direction. The bank contacts may be

arranged to form a complete circle around the shaft of the switch, or they may form only a portion of a circle, and the wipers may each be provided with a plurality of arms 5 so arranged that as one arm passes off the last contact the next arm will engage the first contact. This latter arrangement is shown in Fig. 3, wherein one wiper is shown having three arms 15, 16 and 17. These arms are 10 adapted to engage a bank of contacts containing ten individual segments *a*, and are so arranged that as the arm 15 passes off the last segment the arm 17 engages the first one. In order to avoid the use of wiper 15 cords for connecting the subscribers' lines with the wipers, the banks are made to comprise a common segment 18 situated below and insulated from the individual segments *a*. The wipers may then be simply short- 20 circuiting wipers, so as to connect the common segment 18 with the particular individual contact on which the wipers are resting. For simplicity, the lines are shown connected directly with the wipers in Fig. 1. The 25 motor magnet 14 is provided with means for interrupting its own circuit. A number of means are in use for this purpose, but I find that shown in Fig. 3 to give better results than any others. This interrupting 30 means comprises a pair of springs 19 and 20 which are separated by the bushing on the end of the arm 21, which latter is attached to the armature of the magnet. This arm is so adjusted that it separates the springs 19 35 and 20 just as the armature reaches the completion of its stroke. These springs are, therefore, closed very shortly after the armature begins its return stroke, so that the magnet begins to be energized before the 40 armature is completely retracted. This allows a very rapid operation of the line switch, and makes it possible for the wipers to be rotated over the contacts at a rate of about thirty per second. Also governed by 45 the arm 21 there is a spring 22 which is normally held out of engagement with the spring 20, but which is permitted to engage the spring 20 before the spring 19 is separated therefrom when the magnet 14 is 50 energized. The switch C is also provided with a line relay 24 and a cut-off relay 23, the line relay 24 being connected to the subscriber's line through contacts controlled by said cut-off relay. These relays are inter- 55 locking—that is, in normal position the armature of the relay 24 overlaps the end of the armature of the relay 23, so that if the relay 23 is energized while the relay 24 is in normal position, the armature of the relay 23 60 cannot be pulled all the way up. It can be pulled up far enough, however, to separate all of the springs of the relay from their back contacts, but not far enough to close the front contacts. 65 The first selector D is of the general type

shown in United States Letters Patent No. 815,321, granted March 13, 1906, to Keith, Erickson & Erickson, being modified, however, in order to operate in a so-called two-wire system—that is, a system in which the central office apparatus is controlled over the two sides of the calling line in series. It comprises among other details a set of wipers 25, 26 and 27 carried upon a shaft (not shown) which has a vertical motion 70 controlled by the so-called vertical magnet 28 and a rotary motion controlled by the rotary magnet 29. The usual side switch comprising the wipers 31 and 32 is controlled by the private magnet 33 in a well-known manner. The usual release magnet 34 is provided for restoring the switch to normal position. This release magnet, however, restores the switch immediately upon energization as shown in United States 80 Letters Patent No. 815,176, granted March 13, 1906, to Keith, Erickson & Erickson for connector switches, instead of upon deenergization as shown in said selector patent. The springs 35 and 36 which are included in 85 the release magnet circuit are permitted to close only when the switch shaft is raised one or more steps from its lowest position. The relays 37 and 38 are slow acting relays—that is, slow to deenergize when their 90 circuits are broken. The double-wound line relay 39 is connected with the line through the springs of the line-switching relay 40. In said selector Patent No. 815,321 the rotary magnet armature controls the armature 100 of the private magnet mechanically. In the selector D shown herein, however, the rotary magnet controls the private magnet 33 electrically through the medium of the contact 41. The second selector E is essentially the 105 same as the first selector D. The connector F (Fig. 2) is of the general type of connector switches shown in said connector Patent No. 815,176, being modified, however, like the selector switches, in order to operate 110 in a two-wire system. Associated with the connector there are shown a ringing current generator H and a busy signaling device L. The called substation A' and its line 115 switch C' are in all respects the same as the substation A and the line switch C (Fig. 1). In order to give a clearer understanding of the invention, I will describe in detail how the subscriber at substation A may obtain connection with the subscriber at substation A', the number of which latter will be assumed to be 2220. In the system shown herein, the subscribers' lines are divided into groups, and the individual switches C of all 120 the lines belonging to the same group have common access to the same group of first selectors—that is, each trunk line leading to a first selector is connected in multiple to the 125 corresponding bank contacts of all the in- 130

dividual switches of the group. As has been explained, the individual switches C shown herein do not release and return to normal position upon the termination of the connection. These switches have no normal position, their wipers normally remaining in contact with the trunk line which was last used by the switch. Therefore, it will be seen that when the subscriber at substation 5 initiates a call, the wipers of the switch C may be standing upon the contacts of either a busy trunk or of an idle trunk. If the wipers are standing upon the contacts of an idle trunk, the wipers do not rotate when the 10 subscriber at substation A makes a call, but the relay 23 simply operates to connect the line with the wipers. If the trunk upon which the wipers are standing when the subscriber at substation A makes a call is busy, 15 the wipers are rotated to an idle trunk before the line is connected with them.

When the subscriber at substation A removes his receiver preparatory to making a call, the engagement of the hook switch 20 springs 42 and 43 closes a circuit through the line relay 24 of the switch C, said circuit extending from ground G' through the springs 44 and 45, line 53, springs 42 and 43, 8 and 7, receiver 2, transmitter 3, line 54, springs 30 48 and 47 and the relay 24 to the battery lead 55, thence through battery B to ground G. The relay 24, upon energizing, completes a circuit extending from ground G² through the springs 56, relay 23, interrupter springs 35 20 and 19 and the motor magnet 14 to the battery lead 55. If the wipers of the switch C are standing upon an idle trunk, the closure of this circuit causes the relay 23 to be energized, but the relay 23 being of a comparatively high resistance does not permit sufficient current to flow through the magnet 14 to cause it to be operated. If, however, the wipers of the switch C are standing upon the contacts of a busy trunk line, the wiper 40 12 will be standing upon a contact which is grounded. Therefore, when the relay 24 energizes, the relay 23 will not be energized, because it will be short-circuited over a circuit extending from the grounded private bank 45 contact upon which the wiper 12 is resting, thence through said wiper, springs 51 and 50, springs 57 of the relay 24, thence through the relay 23 and springs 56 of the relay 24 to ground G². The short-circuiting of the relay 23 not only prevents it from energizing, but also causes the motor magnet 14 to be 50 operatively energized. The magnet 14 will, therefore, attract its armature to advance the wipers of the switch one step and to interrupt its own circuit at the springs 19 and 20. If the next trunk is busy also, the wiper 12 will find the next contact grounded, which will cause the motor magnet 14 to be energized again to rotate the wipers another step 55 as soon as the interrupter springs 19 and 20 come into contact. In other words, the motor magnet 14 continues to operate in a manner similar to that of a buzzer to rotate the wipers step by step as long as the wiper 12 continues to engage grounded contacts of busy trunks. As soon as the wiper 12 reaches the non-grounded contact of an idle trunk, the relay 23 ceases to be short-circuited and becomes operatively energized over the circuit traced above. When the 70 relay 23 energizes, the shifting of the springs 45 and 48 disconnects ground G' and the line relay 24 from the calling line, and extends the line connection through the wipers 11 and 13 to a first selector D. 80

When the connection is extended to the first selector, its line relay 39 becomes energized over a circuit extending from ground G³ through the lower winding of said relay, springs 58 and 59, wiper 13, springs 46 and 45, thence to and through the sub-station A and back over the other side of the line through the wiper 11 of the switch C, springs 60 and 61 and the upper winding of the relay 39 to the battery lead. The relay 39, upon energizing, completes a circuit extending from ground G⁴ through the spring 62 and its front contact and the relay 37 to the battery lead. The relay 37, upon energizing, extends a guarding potential from ground G¹⁷ through the springs 63 to the private bank contacts of the trunk leading to the selector D in all of the individual switches which have access to said trunk. The wiper 12 being in contact with the private bank contact of this trunk, a circuit also extends through the springs 51 and 52 and through the relay 23 and magnet 14 to battery. Therefore, the energization of the relay 37 at the selector D provides a holding 100 circuit for the relay 23 to prevent it from being deenergized when its circuit is broken by the line relay 24 after it is disconnected from the line. The engagement of the springs 63 at the selector D also extends a 105 guarding potential back through the switch C and over the conductor 64 to the connector private bank contacts of the calling line. It will be seen that while the motor magnet 14 of the line switch C is operating to 110 rotate the wipers in search of an idle trunk, the spring 22 engages the spring 20 before the spring 20 is separated from the spring 19. Therefore, just before the springs 19 and 20 are finally separated, the magnet 14 115 is not being energized alone by the ground supplied from the guarded private bank contacts through the wiper 12, but also receives current through the ground connection G⁵ and the spring 22. By this arrangement, when the wiper 12 passes off the last grounded contact, there is no circuit interrupted at said wiper and therefore there is no spark to burn the contacts. If 120 it were not for the provision of the spring 125 130

- 22 on the motor magnet, it will be evident that if the wiper 12 left the last grounded contact before the springs 19 and 20 were separated, the operating circuit of the magnet 14 would be broken at the private wiper. This would not only tend to prevent the magnet 14 from completely energizing, but would also cause a spark between the private wiper and its bank contacts, which, 5
- 10 since they were not supplied with platinum contacts, would be very objectionable. The line relay of the switch C is slow acting, so that it will not deenergize and break the circuit of the switching relay 23 until after 15 the relay 37 at the selector D has had time to complete the holding circuit for said relay 23.

The foregoing operations take place immediately upon the removal of the receiver 20 at the calling telephone and before the calling device is operated for the first digit. When the calling device is operated for the first digit 2, the impulse springs 7 and 8 are momentarily separated twice, each time 25 causing the line relay 39 of the selector D to be deenergized momentarily. The relay 37, being slow acting, does not have time to deenergize during the momentary interruption of its circuit by the relay 39, and therefore 30 each time the relay 39 deenergizes, a circuit is closed from ground G^4 through the spring 62 and its back contact, spring 65 and its front contact, relay 38, vertical magnet 28 and side switch wiper 31 to battery lead 55. 35 The digit called being 2, the vertical magnet receives two impulses over this circuit and operates to raise the switch shaft and wipers two steps. The relay 38, which is included in the circuit of the vertical magnet, 40 is energized by the first impulse, but, being a slow acting relay, does not deenergize until after the last impulse is delivered. In its energized position, the relay 38 completes an energizing circuit for the 45 private magnet 33. This circuit is, of course, broken when the relay 38 deenergizes after the last impulse is delivered to the vertical magnet, and the private magnet 33 in turn deenergizes and permits the side 50 switch to pass to second position.

When the side switch wiper 31 engages its second-position contact point, a circuit is closed from ground G^6 through the interrupter springs 66, rotary magnet 29 and side 55 switch wiper 31 to battery. The rotary magnet thereupon begins to operate in a manner similar to that of a buzzer to rotate the wipers step by step in search of an idle trunk line. As soon as the rotary magnet energizes 60 the first time, a circuit is closed from ground G^6 through the contact 41 and private magnet 33 to battery. If the first trunk line upon which the wipers of the selector are rotated is idle, this impulse through 65 the private magnet causes the side switch

to be tripped to third position, thereby completing connection with this trunk line. If this first trunk line is busy, however, the private wiper 26 finds the contact which it engages provided with a guarding ground 70 potential, whereby a locking circuit is completed from said grounded bank contact through the wiper 26, side switch wiper 32 (in second position) and private magnet 33 to battery. The closure of this holding 75 circuit through the private magnet prevents the private magnet from deenergizing when the contact 41 is opened, and thereby causes the side switch to be locked in second position, and the rotary magnet continues to advance the wipers step by step until an idle trunk is found. When the wiper 26 leaves the contact of the last busy trunk, the holding circuit of the private magnet is broken and the side switch passes to third position. 80 The movement of the side switch wiper 31 from second to third position breaks the operating circuit of the motor magnet and closes the circuit of the line-switching relay 40. This circuit extends from ground G^{17} 85 through the spring 63, relay 40 and side switch wiper 31 to battery. The relay 40, upon energizing, disconnects the line relay 39 from the line and extends the connection over the heavy conductors through the wipers 27 and 25 to the second selector E. The line relay 68 of the second selector thereupon becomes energized in the same manner as explained for the line relay 39 of the selector D. The relay 68, upon energizing, 90 closes the circuit of the relay 69, which corresponds with the relay 37 of the first selector D. The relay 69, upon energizing, extends a holding circuit from ground G^7 95 through the springs 70, private wiper 26 of the selector D, side switch wiper 32, relay 40 and side switch wiper 31 to battery. The closure of this circuit maintains the relay 40 energized after its original energizing circuit is broken by the deenergization of 100 the relay 37, which takes place shortly after the line relay 39 is disconnected from the line and allowed to deenergize. The closure of the springs 70 of the relay 69 of the selector E also provides a guarding potential for 105 the selector private bank contacts of the trunk leading to the selector E, and also substitutes ground G^7 for ground G^{17} at the selector D in the holding circuit of the line relay 23 of the switch C. The new holding circuit for the relay 23 includes the side switch wiper 32 at the selector D, which 110 is now in third position.

The subscriber at substation A now operates his calling device for the second digit 115 2. The second selector E operates in the same manner for this digit as explained for the selector D. The operation of the selector E extends the connection over the trunk conductors 72 and 73 to a connector F 120

(Fig. 2). When a connection is extended to the connector F, the line relay 74 becomes energized in the same manner in which the line relays of the selector switches are energized when connection is first extended to them. The relay 74, upon energizing, completes a circuit through the slow acting release relay 75. The relay 75, upon energizing, establishes a holding circuit for the relays 80, 81 and 93 of the switches C, D and C'. This circuit extends from ground G¹ through the side switch wiper 76, springs 77, conductor 71, private wiper 78 of the selector F, side switch wiper 79, from which point the circuit divides into two branches, one branch passing through the relay 80 and side switch wiper 81 to battery, while the other branch passes on back through the private wiper 89 of the selector D and side switch wiper 82, where it again divides into two branches, one branch passing through the relay 86 to battery, while the other branch passes on back to and through the relay 86 over a circuit which has already been pointed out.

The apparatus is now in position to receive the impulses for the third digit 2. The separation of the substation impulse springs 7 and 8 for this digit breaks the energizing circuit of the line relay 74 of the connector F. The relay 75, being slow acting, does not deenergize during the momentary interruption of its circuit by the relay 74. Therefore, each time the relay 74 deenergizes, a circuit is completed from ground G¹ through the spring 82 and its back contact, spring 83 and its front contact, vertical magnet 84, side switch wiper 85 and the relay 86 to the battery lead 53. The digit called being 2, the vertical magnet receives two impulses over this circuit, operating in response thereto to raise the wipers 87, 88 and 89 two steps. The slow acting relay 86, which is included in the circuit of the vertical magnet, is energized by the first impulse, and remains in its operated position until after the last impulse is delivered. The relay 86, upon energizing, completes a circuit from ground G¹ through the springs 80 and 91 and the private magnet 92 to battery. The private magnet, upon energizing and de-energizing, causes the side switch to pass from first to second position after the vertical magnet has completed its operation. Upon the substation calling device being operated for the last digit 2, the circuit for line relay 74 deenergizes for time. Since the side switch is in second position, the de-energization of the relay 81, in response to the impulses for the last digit, completes the circuit of the rotary magnet 102. This circuit extends from ground G¹ through the spring 82 and its back contact, spring 83 and its front contact, springs 94, magnet 93, side switch wiper 85 and relay 86 to bat-

tery. The rotary magnet receives ten impulses over this circuit and operates to advance the wipers ten steps onto the contacts of the line No. 2220. The relay 86 operates, in response to the impulses for the last digit, in the same manner as for the preceding digit to cause the private magnet to step the side switch around one more step after the last impulse is delivered to the rotary magnet. This movement of the side switch wipers 85 and 96 from second to third position completes the connection between the calling and the called lines. The side switch wiper 97, upon reaching third position, completes a circuit extending from ground G¹ through the side switch wiper 97, springs 98 and 99, private wiper 89, cut-off relay 100 of the switch C', springs 101 and 102 and magnet 103 to battery. The magnet 103 is not operated over this circuit owing to the high resistance of the relay 100, but the relay 100 operates to separate the springs 104, 105 and 106 from their back contacts, so as to disconnect the switch C' from the called line. Since the relay 107 is not energized, the armature of the relay 100 cannot be pulled up far enough to close the contact between the springs 104, 105 and 106 and their front contacts. It will thus be seen that when the connection is extended to the line to which the switch C' belongs, the relay 100 operates to disconnect the switch from the line, but does not operate to connect the line with the wipers, as it would in case the line A' were a calling line. It will be seen that in the circuit traced through the relay 100 a connection was traced from ground G¹ to the private wiper 89. This provides a guarding potential for the connector private bank contacts of the called line in the banks of all connectors which have access to it. The engagement of the side switch wiper 85 with its third-position contact point completes a circuit from ground G¹² through the interrupter 108, springs 109, ringing relay 110, side switch wiper 85 and relay 86 to battery. The relay 110, upon energizing, disconnects the calling line from the called line, and connects the ringing current generator H with the called line to signal the called subscriber. Since the circuit of the relay 110 includes the interrupter 108, said relay is energized only intermittently so as not to ring the called subscriber continuously. When the called subscriber answers, or as soon thereafter as the relay 110 deenergizes, if it happens to be energized at the time, the called substation is provided with talking current over a circuit which extends from ground G¹ through the side switch wiper 97, lower winding of the connector back-bridge relay 112, ringer relay 113, springs 114 and 115, side switch wiper 96, shaft wiper 88, thence to and through the called substation A' and back over the other

side of the line through the wiper 87, side switch wiper 95, springs 115 and 116 and the upper winding of the relay 112 to battery. The relay 112, upon energizing, separates the springs 109, thereby breaking the circuit of the ringing relay 119 so as to prevent further application of ringing current to the called line after the called subscriber answers. The complete talking circuit between the calling and called substations is outlined by heavy conductors in the drawings.

After the conversation is completed, the connection is released by the hanging up of the receiver at the calling substation. It will be seen that when the side switch wiper 73 of the connector passes to third position, the holding circuit of the relays 89, 10 and 23 of the switches E, D and C is transferred from ground G¹ to ground G² through the springs of the line relay 74. When the calling subscriber hangs up his receiver, the connector line relay 74 deenergizes, immediately breaking the holding circuit of the relays 89, 10 and 23, as well as the circuit of its own release relay 75. The relay 75, upon deenergizing, closes the circuit of the release magnet 117. This circuit extends from ground G² through the spring 82 and its back contact, spring 83 and its back contact, magnet 117 and the off normal springs 118 to battery. The relay 10 of the selector D upon deenergizing, completes the circuit of the release magnet 34 as follows: ground G¹, spring 92 and its back contact, spring 119 and its back contact, springs 120, off normal springs 35 and 36 and magnet 34 to battery. In like manner, the relay 89, upon deenergizing, closes the circuit of the release magnet 120 of the selector E. The release magnets 117, 120 and 34, upon energizing, immediately restore their respective switches to normal position, and these magnets are all deenergized by the separation of their off normal springs as soon as the switch shaft of each switch reaches its lowest position. The relay 23 of the switch C, of course, deenergizes when its circuit is broken by the deenergization of the line relay of the connector, and disconnects the line from the wipers 11, 12 and 13, but leaves these wipers resting upon the contacts of the trunk line.

In the foregoing description it has been assumed that the calling line is idle when the wipers of the connector E engage its contacts. If this line had been busy, the connector E would not have connected the calling line therewith, and would have caused the calling subscriber to be given the busy signal in the following manner: It is evident from the preceding description that whenever a line is busy, its connector private bank contacts are provided

with a guarding ground potential. Therefore, at the time that the wipers of the connector engage the contacts of a busy line, a ground potential is extended from its guarded private bank contact through the private wiper 89, springs 99 and 98, lower winding of the relay 112, ringer relay springs 113 and 114 and the side switch wiper 96, which is then in second position, to the private magnet relay spring 121. As the private magnet relay 86 deenergizes, after the last digit is called, the spring 121 engages the spring 91 before the springs 90 and 91 are separated. The engagement of the springs 121 and 91 further extends the ground connection from the guarded private bank contact through the private magnet 92 to battery. The private magnet is, therefore, not deenergized by the deenergization of the relay 86, but remains energized in series with the lower winding of the relay 112. Since the private magnet does not deenergize, the side switch remains locked in second position, and the connection between the calling and the called lines is not completed at the side switch wipers 92 and 96. The relay 112 being included in the locking circuit of the private magnet is operatively energized, and operates in conjunction with said magnet to complete a circuit from ground G¹ through the springs 90 and 122, springs 123, relay 124 and springs 125 to battery. The relay 124, upon energizing, shifts the holding circuit of the private magnet and the relay 112 from the guarded private bank contacts to ground G² by way of the springs 126 and 98. The side switch of the connector will, therefore, remain locked in second position until the calling subscriber hangs up his receiver, and during this time the busy signaling machine L is connected with the calling line through the springs 127 of the relay 124, contact point 128, side switch wiper 95, springs 115 and 116 and condenser 129. The return circuit for the busy signaling current is through the lower winding of the line relay 74 of the connector, thence to ground G² and through battery B back to the machine L. When the receiver at the calling substation is hung up, the apparatus is released in substantially the same manner as when a complete connection has been established.

While I have illustrated and described a particular type of automatic telephone system employing my improved line switch, it is to be understood that I do not wish to limit myself to such use, as it is obvious that the line switch of my application could be equally as well employed in other automatic or semi-automatic systems, and it might be used in any location where it is desired to automatically select an idle

trunk, whether this trunk extends to an automatic switch or to an operator's position.

What I claim as my invention is:—

1. In a telephone system, a subscriber's line, trunk lines, a trunking switch for said subscriber's line for selecting an idle trunk, the wipers of said switch normally engaging one of said trunk lines, a line relay normally connected with said line, a cut-off relay, means controlled by said cut-off relay for cutting off said line relay from the line when said subscriber's line is either calling or being called, means controlled by said cut-off relay for connecting said line with one of said trunks when said line is calling, and means including an automatic switch for extending a connection to the called line.
2. In a telephone system, a subscriber's line, a non-numerical trunking switch therefor, trunk lines for talking purposes, said switch including line wipers always in electrical engagement with one of said trunk lines, a relay in said switch, a cut-off relay, means controlled by said cut-off relay for opening the circuit of said first-mentioned relay when said line is calling or being called, and means controlled by said cut-off relay for connecting said line wipers with said subscriber's line.
3. In a telephone system, a subscriber's line, a non-numerical trunking switch therefor, trunk lines for talking purposes, said switch including line wipers always in electrical engagement with one of said trunk lines, a line relay in said switch normally connected with the subscriber's line, a cut-off relay, means controlled by said cut-off relay for cutting off said line relay when said line is calling or being called, and means controlled by said cut-off relay for connecting said line wipers with said subscriber's line.
4. In a telephone system, a non-numerical trunking switch, trunk lines for talking purposes leading therefrom, said switch including line wipers always in electrical engagement with one of said trunk lines, a slow acting line relay for controlling the operation of said switch, a cut-off relay, means controlled by said cut-off relay for opening the circuit of said line relay, and means controlled by said line relay for controlling the extent of operation of said cut-off relay.
5. In a telephone system, a non-numerical trunking switch, trunk lines for talking purposes leading therefrom, a line relay controlling the operation of said switch, a cut-off relay for controlling the circuit of said line relay, and means controlled by said line relay for mechanically controlling the extent of operation of said cut-off relay.
6. In a telephone system, a non-numerical trunking switch, trunk lines for talking purposes leading therefrom, said switch having line wipers always in electrical engagement with one of said trunk lines, a line relay controlling the operation of said switch, a cut-off relay, means controlled by said cut-off relay for opening the circuit of said line relay, and means controlled by said line relay for mechanically controlling the extent of operation of said cut-off relay.
7. In a telephone system, a non-numerical trunking switch, trunk lines for talking purposes extending therefrom, a line relay controlling the operation of said switch, a cut-off relay controlling the circuit of said line relay, and means controlled by said line relay for mechanically controlling the extent of operation of said cut-off relay.
8. In a telephone system, a non-numerical trunking switch, a line relay for controlling the operation of said switch, a cut-off relay having both front and back contacts, and means controlled by said line relay whereby in normal or deenergized position the cut-off relay is prevented from closing its front contacts, but is permitted to open its back contacts.
9. In a telephone system, a non-numerical trunking switch, trunk lines for talking purposes leading therefrom, said switch having line wipers always in electrical engagement with some one of said trunk lines, a line relay for controlling the operation of said switch, a cut-off relay having both front and back contacts, means controlled by said line relay whereby when said line relay is deenergized said cut-off relay is adapted to open its back contacts to open the circuit of said line relay, but is prevented from closing its front contacts to extend connection to said trunk line.
10. In a telephone system, a line switch, a line relay therefor, and a switching relay for cutting off the line relay and closing the line through the switch, said switching relay being operative to perform both its functions when the line is calling, but being operative to cut off the line relay and inoperative to close the line through when the line is called.
11. In a telephone system, a line switch, a line relay therefor, a cut-off relay, said cut-off relay being operative to cut off the line relay and close the line through if it is energized while the line relay is energized, but which is operative to cut off the line relay and inoperative to close the line through if it is energized while the line relay is deenergized.
12. In a telephone system, an automatic switch including a relay having both front and back contacts, a second relay, and means

- whereby the second relay when in normal or deenergized position renders the first-mentioned relay inoperative to close its front contacts, but permits it to open its back contacts.
13. In a telephone system, a subscriber's line, trunk lines, a trunking switch for said subscriber's line for selecting an idle trunk, a slow-acting line relay normally connected with said line, a cut-off relay, means controlled by said cut-off relay for cutting off said line relay from the line when said subscriber's line is either calling or being called, and means controlled by said cut-off relay for connecting said line with one of said trunks when said line is calling.
14. In a telephone system, a subscriber's line, trunk lines, a trunking switch for said subscriber's line, a line relay normally connected with said line, an operating magnet controlled by said line relay, a cut-off relay, a test conductor for each trunk, automatic means for applying a potential to said test conductor, said operating magnet being responsive to said potential to move said switch progressively over said trunks until a trunk is found without such potential on its test conductor, means controlled by said cut-off relay for cutting off said line relay from the line when said subscriber's line is either calling or being called, means controlled by said operating magnet for directly controlling the circuit of said cut-off relay, and means controlled by said cut-off relay for connecting said line with one of said trunks when said line is calling.
15. In a telephone system, a subscriber's line, trunk lines, a trunking switch for said subscriber's line for selecting an idle trunk, a line relay normally connected with said line, a cut-off relay, means controlled by said cut-off relay for cutting off said line relay from the line when said subscriber's line is either calling or being called, means controlled by said cut-off relay for connecting said line with one of said trunks when said line is calling, and a short-circuit for said cut-off relay controlled by said line relay to prevent the operation of said cut-off relay when a busy line is found.
16. In a telephone system, a non-numerical trunking switch, trunk lines for talking purposes extending therefrom, a line relay controlling the operation of said switch, a cut-off relay controlling the circuit of said line relay, means controlled by said line relay for mechanically controlling the extent of operation of said cut-off relay, and wipers for said switch normally engaging one of said trunk lines.
17. In a telephone system, a non-numerical trunking switch, a line relay for controlling the operation of said switch, a cut-off relay having both front and back contacts, means controlled by said line relay whereby in normal or deenergized position the cut-off relay is prevented from closing its front contacts, but is permitted to open its back contacts, and wipers for said switch normally engaging one of said trunk lines.
18. In a telephone system, a line switch, a line relay therefor, a switching relay for cutting off the line relay and closing the line through the switch, said switching relay being operative to perform both its functions when the line is calling, but being operative to cut off the line relay and inoperative to close the line through when the line is called, and wipers for said switch normally engaging one of said trunk lines.
19. In a telephone system, a line switch, a line relay therefor, a cut-off relay, said cut-off relay being operative to cut off the line relay and close the line through if it is energized while the line relay is energized, but which is operative to cut off the line relay and inoperative to close the line through if it is energized while the line relay is deenergized, and wipers for said switch normally engaging one of said trunk lines.
20. In a telephone system, a subscriber's line, trunk lines, a trunking switch for said subscriber's line, a line relay normally connected with said line, an operating magnet controlled by said line relay, a cut-off relay, means controlled by said cut-off relay for cutting off said line relay from the line when said subscriber's line is either calling or being called, means controlled by said operating magnet for directly controlling the circuit of said cut-off relay, means controlled by said cut-off relay for connecting said line with one of said trunks when said line is calling, the wipers of said switch normally engaging one of said trunk lines.
21. In a telephone system, a subscriber's line, trunk lines, a trunking switch for said subscriber's line for selecting an idle trunk, the wipers of said switch normally engaging one of said trunk lines, a line relay normally connected with said line, automatic means for progressively moving said switch upon energization of the line relay, automatic means for stopping said switch without further action on the part of the line relay, a cut-off relay, means controlled by said cut-off relay for cutting off said line relay from the line when said subscriber's line is either calling or being called, and means controlled by said cut-off relay for connecting said line with one of said trunks when said line is calling.
22. In a telephone system, a subscriber's line, a non-numerical trunking switch therefor, trunk lines for talking purposes, said switch including line wipers always in electrical engagement with one of said trunk lines, a relay in said switch, automatic means for progressively moving said switch upon the energization of the relay, automatic

- means for stopping said switch without further action on the part of the relay, a cut-off relay, means controlled by said cut-off relay for opening the circuit of said first-⁵ mentioned relay when said line is calling or being called, means controlled by said cut-off relay for connecting said line wipers with said subscriber's line.
23. In a telephone system, a subscriber's line, a non-numerical trunking switch therefor, trunk lines for talking purposes, said switch including line wipers always in electrical engagement with one of said trunk lines, a line relay in said switch normally connected with the subscriber's line, automatic means for progressively moving said switch upon energization of the line relay, automatic means for stopping said switch without further action on the part of the line relay, a cut-off relay, means controlled by said cut-off relay for cutting off said line relay when said line is calling or being called, means controlled by said cut-off relay for connecting said line wipers with said subscriber's line.
24. In a telephone system, a non-numerical trunking switch, trunk lines for talking purposes leading therefrom, said switch including line wipers always in electrical engagement with one of said trunk lines, a slow acting line relay for controlling the operation of said switch, automatic means for progressively moving said switch upon energization of the line relay, automatic means for stopping said switch without further action on the part of the line relay, a cut-off relay having both front and back contacts, means for controlling said line relay whereby when said line relay is deenergized said cut-off relay is caused to open its back contacts to deenergize the coil of said line relay, but is prevented from closing its front contacts to open the line through to said trunk line.
25. In a telephone system, a non-numerical trunking switch, trunk lines for talking purposes leading therefrom, a line relay controlling the operation of said switch, automatic means for progressively moving said switch upon the energization of the line relay, automatic means for stopping said switch without further action on the part of the line relay, a cut-off relay for controlling the circuit of said line relay, means controlled by said line relay for mechanically controlling the extent of operation of said cut-off relay.
26. In a telephone system, a non-numerical trunking switch, trunk lines for talking purposes leading therefrom, said switch having line wipers always in electrical engagement with one of said trunk lines, a line relay controlling the operation of said switch, automatic means for progressively moving said switch upon energization of the line relay, automatic means for stopping said switch without further action on the part of the line relay, a cut-off relay, means controlled by said cut-off relay for opening the circuit
- of said line relay, and for extending connection to said trunk lines, means controlled by said line relay for mechanically controlling the extent of operation of said cut-off relay.
27. In a telephone system, a non-numerical trunking switch, trunk lines for talking purposes extending therefrom, a line relay controlling the operation of said switch, automatic means for progressively moving said switch upon energization of the line relay, automatic means for stopping said switch without further action on the part of the line relay, a cut-off relay controlling the circuit of said line relay, means controlled by said line relay for mechanically controlling the extent of operation of said cut-off relay.
28. In a telephone system, a non-numerical trunking switch, trunk lines for talking purposes leading therefrom, said switch including line wipers always in electrical engagement with one of said trunk lines, a line relay for controlling the operation of said switch, automatic means for progressively moving said switch upon energization of the line relay, a cut-off relay, means controlled by said cut-off relay for opening its back contacts to deenergize the coil of said line relay, but is prevented from closing its front contacts to open the line through to said trunk line.
29. In a telephone system, a line switch, a line relay therefor, automatic means for progressively moving said switch upon energization of the line relay, automatic means for stopping said switch without further action on the part of the line relay, a switching relay for cutting off the line relay and closing the line through the switch, said switching relay being operative to perform both its functions when the line is calling, but being operative to cut off the line relay and inoperative to close the line through when the line is called.
30. In a telephone system, a line switch, a line relay therefor, automatic means for progressively moving said switch upon energization of the line relay, automatic means for stopping said switch without further action on the part of the line relay, a cut-off relay, said cut-off relay being operative to cut off the line relay and close the line through if it is energized while the line relay is energized, but which is operative to cut off the line relay and inoperative to close the line through if it is energized while the line relay is deenergized.
31. In a telephone system, an automatic switch including a relay having both front and back contacts, a second relay means whereby the second relay when in normal or deenergized position renders the first me-¹²⁰

tioned relay inoperative to close its front contacts, but permits it to open its back contacts, automatic means for progressively moving said switch upon the energization of the said second relay, and automatic means for stopping said switch without further action on the part of the said second relay.

Signed by me at Chicago, Cook county, Illinois, this 17th day of August, 1911.

WILLIS E. LAMB.
